Fig. 1.

CHART

Line
"AB" Batter only—with
no one on base

1 — Runner on 1st base — No outs
2 — Runner on 1st base — One out
3 — Runner on 1st base — Two out
4 — Runner on 2nd base — No outs
5 — Runner on 2nd base — One out
6 — Runner on 2nd base — Two out
7 — Runner on 3rd base — No outs
8 — Runner on 3rd base — One out
9 — Runner on 3rd base — Two out
10 — Runner on 1st & 2nd — No outs
11 — Runner on 1st & 2nd — One out
12 — Runner on 1st & 2nd — Two out
13 — Runner on 2nd & 3rd — No outs
14 — Runner on 2nd & 3rd — One out
15 — Runner on 2nd & 3rd — Two out

16 — Runner on 1st & 3rd — No outs
17 — Runner on 1st & 3rd — One out
18 — Runner on 1st & 3rd — Two out
19 — Bases full — No outs
20 — Bases full — One out
21 — Bases full — Two out

Sacrifices

22 — From 1st to 2nd base
23 — From 2nd to 3rd base
24 — From 3rd base to home
25 — From 1st & 2nd to 2nd & 3rd
26 — Bases full

Stolen Bases

27 — From 1st to 2nd base
28 — From 2nd to 3rd base
29 — From 1st & 2nd to 2nd & 3rd
30 — From 1st & 3rd to 2nd & home
31 — From 3rd base to home

32 — Hit & run play, 1st to 2nd base
To be used only with man on 1st
base and none or one man out.

BASEBALL GAME

William H. Parker and David P. Gregory, Richmond, Va., assignors of one-third to said Parker and two-thirds to said Gregory

Application September 10, 1934, Serial No. 743,448

6 Claims. (Cl. 273—93)

This invention relates to a game of baseball, and particularly one which is played by a number of players, such as two or more, and in which a means, preferably a deck of specially constructed and marked cards is used in combination with an indicating means which may take the form of a chart, and score cards.

An object of the invention is to provide a baseball card game, based upon the science of baseball, and which insures the faithful following out of the various plays, such as take place during the playing of a game of baseball, and such plays as actually occur when teams of the major leagues oppose each other.

Another object of the invention is to provide a baseball card game in the playing of which the "breaks of the game" occur substantially in the same manner and sequence as in a big league game.

Another object of the invention is to provide a baseball game, the plays of which are controlled equally by both sides, or by the teams which oppose each other.

Still another object of the invention is to provide a game of the character described, during the playing of which, advantage is taken both of the element of luck and as the result of the skill of the respective players.

A further object is to provide a game of the class described, which so faithfully represents the various and intricate plays of baseball as to be fully adapted for use in the teaching of "inside baseball", or "skull practice", and one that is instructive to beginners as well as to students of the game.

Another object is to provide a "home baseball game", simulating the game of baseball, the cards being adapted to be so played as to produce, in effect, every play made in the playing of a real game of baseball.

Various other objects and advantages will be more fully set forth in the accompanying specification and drawings, which exemplify a preferred form of our invention.

In the drawings:—

Figure 1 illustrates a chart, setting forth the various conditions of play of a baseball game;

Figure 2 discloses one of the cards having thereon a series of lines, having on said lines data, indicating the various plays of the game and the results of said plays; and

Figure 3 discloses another of the cards similar to Figure 2.

The primary purpose of the card game comprising this invention is to so closely adhere to

the science and strategy of the modern baseball game, particularly as played by teams of the major leagues and according to the official rules of the game, that the game is capable of teaching the fine points of major league baseball to students of the game, and affords considerable amusement while so doing.

A means, one form of which is shown by Figure 1 is provided for indicating which line on any one of a series of means, herein shown as cards, 10 is applicable with a given "situation". The indicating means may consist of a chart mounted on a sheet as shown in Figure 1, but any other suitable means may be substituted for the chart, such as a board having separate structurally distinctive means such as buttons or representations of the play, etc. suitably designated either colored or uncolored, indicative of the various possible "situations" occurring in big league baseball. Such "situations" are shown as 32 in number in addition to "situation" AB, on the chart shown on Figure 1, but this number may be increased or decreased, as this invention is not limited to the number shown, although the number given is the preferred form of our invention.

Each of the cards, preferably sixty in number, two of which are shown by way of example in Figures 2 and 3, contain play "AB" and 32 additional plays corresponding to the "situations" given on the chart. Each "situation" on the chart is connected to the play or action to follow as given by the cards, as a result of said "situation", by corresponding numbers on the cards and chart with the exception of "AB" (batter up with none, one or two out and no players on bases). Al-

though not shown, the means for connecting each "situation" on the chart with the play on each card to which it corresponds, may consist of a series of notches or perforations on the chart and cards. For instance, each card instead of having the numeral may be provided with a single notch or perforation which will correspond to a single notch or perforation on the chart, in place of the numeral 1 on said chart. In place of numeral 2 on the chart and cards, two notches or perforations may be used, or some other designation such as a small cut out crescent, horseshoe, X, T, or other letter, or other designating means. During the playing of the game, when a given "situation" has been located on the chart, the cut out "T", or other designating cut out means on the chart is placed above or beneath the "T" or other designating means on the card that has been turned, which will serve to keep the play and "situation" in mind until the next play with the

new "situation" is made. The chart may have the designating means printed thereon, while each card has cutout different characters which correspond to the printed characters. When the proper "situation" has been found on the chart the card is removed from the top of the deck and the next card from the deck is placed on top of the chart and moved around until the cut out "T" or other character aligns with the printed 5 "T" beneath it, thereby providing an indication of the progress of the game while studying the "situation" before deciding the next move which may be a stolen base, sacrifice hit and run play in addition to the other first given 21 situations, 10 and situation "AB" on the chart.

When the device as shown by the drawings is used, the game is played as follows: A coin may be tossed to determine which "captain" or "team manager" will be the "home team", and which 15 20 the "visiting team." The "visiting team" will be first at bat.

The first line on each of the play indicating means herein shown as playing cards is indicated "AB" by lettering, perforations or otherwise, and 25 25 the "AB" play is always the correct play to make with no runners on base (either with none, one or two outs).

The captain, therefore of the "home team" will 30 shuffle the cards (his team being in the field at the start of the game), and turn the uppermost card. The card below that which has been turned is read on the line opposite "AB", which reading matter indicates the first play. Example: The 35 card reads "Single to LF". The captain of the "visiting team" now consults the chart until he finds the proper "situation"; that is, the line which states "Runner on first base—no outs". On the same line with this statement is an indicating means such as a numeral or cutout portion. 40 The next uppermost card is now again turned by the "visiting captain", and the next card is consulted and the numeral or cutout portion found which corresponds to that on the chart opposite the words "Runner on first base—no outs". Opposite 45 this numeral or cutout portion on the card will be found the play. Example: The card reads "Grounder to short stop. Batter out at first. Runner to second base". The "situation" now is; one man out and one man on second base.

50 The captain of the visiting team now consults the chart and finds that with a man on second base and one out the line indicated by numeral 5 (if numerals are used as the indicating means), is the proper "situation". The captain of the 55 home team (now in the field), turns the uppermost card and reads the play given opposite numeral 5. Example: The card reads "Base on balls". This results in the "visitors" having one man on first base and one man on second base 60 and one man out. The captain at bat consults the chart and finds that line 11 is the correct play to call. The captain in the field turns the next card and reads the play opposite the figure on the next uppermost card. Example: The card 65 reads "Fly to center field, batter out". The result of the play is that the visiting team has men on first and second bases, with two men out. Upon consulting the chart the captain of the visiting team finds that line 12 corresponds to this condition. The captain of the team in the 70 field turns a card and reads the play given opposite number 12. Example: The card reads "Three base hit". This play scores the runners on first and second bases and leaves a man on third base with two outs.

The captain of the visiting team (at bat), upon consulting the chart finds that the condition specified (two out and one on third base) calls for number 9. The captain in the field turns the next card. Example: The card reads opposite number 9 thereon the following: "Strike out". The visiting team having three outs is retired to the field and the home team takes its turn at bat until three outs occur, as shown above. The game is continued for nine innings or longer, if the 10 sides are tied, and until one side has the most runs, in the same manner as a regular game between real teams.

After the players become familiar with the playing of the game, certain innovations may be 15 used, under certain circumstances, as follows, which include the decision to use the hit and run play, sacrifice plays and stolen base plays.

The captain of the team in the field turns the uppermost card and reads from the next card 20 the words (for example) opposite "AB", "Base on balls". The captain of the team at bat then decides to try the "hit and run play" instead of number 1 on the chart, which reads "Man on first base—no outs". Referring to the chart, he finds 25 the hit and run play to be numbered 32. The uppermost card is turned and the play opposite numeral 32 on the next card is read. Example: The card reads, "Grounder to short stop. Batter out at first base. First base runner to second base". With one man on second base and one man out, the captain of the team at bat may decide to try a stolen base play instead of playing the game by consulting the chart to find a number indicating the "situation" of one man 30 on second base and one out (number 5). Line 28 corresponds to the condition where it is desired to try a "steal", from second to third base. The uppermost card is turned and number 28 looked up on the card which is now uppermost. Example: The card says "Runner safe at third base". There is now one man on third base, and one out. If it is now desired to try the sacrifice hit, the chart is consulted and it is found that 24 indicates the proper condition for this play. The 40 uppermost card is turned and the next card reads (for example), "Batter safe at first base. Runner 45 3 out at home plate". This makes two outs with one man on first base. The captain at bat now calls for the regular play (line 3 on chart), and upon turning the uppermost card, reads the play under number 3, which reads (for example), "Grounder to short stop. Batter out at first base". This play retires the side and allows the other side to come to bat unless the nine innings 55 without tie have been played.

If the team in the field is having a number of runs scored against it, a new pitcher can be understood to have been placed in the box. This is accomplished by the captain of that team cutting 60 the cards. If the score is close a pinch hitter can be used by the team at bat, this being understood as having been accomplished when the captain of the team at bat cuts the cards.

By reference to the cards, the following should 65 be understood: Runner on first base is indicated "R1"; runner on second base is indicated "R2"; runner on third base is indicated "R3"; batter is indicated "X"; pitcher is indicated "P"; catcher is indicated "C".

The various positions in the field and/or the 70 players at such positions are indicated as 1B, 2B, 3B, plate, SS, RF, CF and LF.

In order to keep an accurate record of the 75 progress of the game, each player may be pro-

vided with a score card of the kind ordinarily used at baseball games. If it be presumed that the New York Giants are playing the New York Yankees, the line-up of each team is written on each card, including the names of the players. As the game progresses the hits, bases on balls, strike-outs and errors of each player are recorded on each score card, as they occur, opposite the name of the player who makes the various plays, in the same manner as if the players of the game were witnessing and keeping score as at an actual baseball game played in the field between these teams. In the instant case, however, the players of the game are not only spectators of the game but each has one of the opposing teams to manage and each must, accordingly, make certain decisions, depending on the circumstances of the play of the game, concerning, for example, whether to try a stolen base play, make a sacrifice play, a hit and run play, or whether to continue to play straight baseball and omit said plays.

The invention preferably embraces the use of 60 cards as it has been found that this number is about the number of men at bat in an ordinary baseball game. If the game requires more than 60 plays and all the cards have been turned, the cards are used over again, preferably by turning for a second time the card turned at the beginning of the game. Where the cards have been cut, such as when the team in the field decides to use a new pitcher, the cards are turned in the sequence by which they have been cut. The cards must be shuffled at the end of each half inning.

The plays as listed on each card have been worked out as a result of scientific analysis of a large number of big league baseball games to determine the average number of bases on balls, strike-outs, home-runs, 1 base, 2 base, 3 base hits, double plays, bunts, etc. For instance, in the average big league game, only one home run, four strike outs, five walks, two two-baggers, etc. may occur. In playing the game of this invention, sometimes, more than and sometimes less than the average number of home runs, etc. will occur in each game, but it has been found that in say, one hundred games as played, using this invention, the same number of similar plays will occur as occurred in the actual playing of one hundred big league games. Similarly, the average game when played as taught by this invention, will contain the average number of plays, such as home runs, bases on balls, etc., that will occur in a big league game. Also, the proportion of runs to the number of hits in each game has been worked out to be the same in the playing of the game of this invention, as will be the case in an actual big league game. The proportion of each of the other plays to each other has been so worked out that in the playing of the present game they occur in the same proportion as they occur in a game between teams of the major leagues. This co-relation of the various cards, is considered to be one of the most important objects of this invention.

While the form of the invention herein shown and described is fully adapted to fulfill all of the objects herein recited, it is to be understood that we do not desire to limit the invention in this regard, as the invention is capable of embodiment in various other forms, all within the scope of the following claims.

We claim:—

1. A baseball card game including a plurality

of cards, each having thereon a plurality of serially listed plays, identifying means located opposite each play and a situation means designating the situation on the ball field following each play and having a plurality of identifying means corresponding in number with the number of listed plays on said cards whereby each identifying means on said situation means corresponds to an identifying means on each of the said cards and a series of additional alternative situations on said chart which may be used at the discretion of the players, and plays on each card to be followed as a result of each situation when selected, and corresponding identifying means on said chart and cards. 5

2. A baseball card game comprising a plurality of cards each having thereon a series of plays separately identified by designating means opposite each play, and means corresponding in number to the number of the plays and being separate from said cards designating the situations on the baseball field following each play and having indicating means for each situation which refers by the same designating means on the several cards to a different play following each 10 of said situations, whereby upon selecting a card from the pack an appropriate, but previously unknown play will be indicated as following each situation and a series of additional alternative situations on said chart which may be used at 15 the discretion of the players, and plays on each card to be followed as a result of each situation when selected, and corresponding identifying means on said chart and cards. 20

3. A baseball game which comprises, in combination, a key chart having thereon consecutively arranged all of the known situations following a play in baseball, a separate distinguishing designation opposite each of said situations, and a plurality of cards each of which is provided with designations corresponding in number to those indicating the situations on the chart and indicating on each card a previously unknown play to follow from the situation to which reference is made through the designations, said plays 30 varying on the different cards but representing any play which may be made from the situation as indicated on the chart and a series of additional alternative situations on said chart which may be used at the discretion of the players, and plays 35 on each card to be followed as a result of each situation when selected, and corresponding identifying means on said chart and cards. 40

4. A baseball card game comprising a chart having thereon a series of indicated positions of a player or players in a game of ball, including the position of said player or players on one or more bases, and the number of outs of the side being represented, each of said indicated positions being provided with an individual indicating means, in combination with a deck of cards each of which has thereon means to indicate any series of a plurality of plays which may follow any one of the positions on the chart, said plays being provided with an indicating means 50 which corresponds in number to the several indicating means on the chart, whereby when any card is drawn from the pack one of a possible plurality of plays is ascertained by the corresponding indicating means of the position of the 55 player or players last determined from the chart and a series of additional alternative situations on said chart which may be used at the discretion of the players, and plays on each card to be followed as a result of each situation when selected, and corresponding identifying means on said chart and cards. 60

lected, and corresponding identifying means on said chart and cards.

5. A baseball game including a plurality of means each having thereon a plurality of serially listed plays, identifying means located opposite each play and a situation means designating the situation on the ball field following each play and having a plurality of identifying means corresponding in number to the listed number of plays 10 of said first mentioned means whereby each identifying means on said situation means corresponds to identifying means on said first named means and a series of additional alternative situations on said chart which may be used at the discretion of the players, and plays on each card 15 to be followed as a result of each situation when selected, and corresponding identifying means on said chart and cards.

6. A baseball card game comprising, in combination, a chart having thereon consecutively ar- 20

ranged designations for the various situations found in playing a game of baseball, a separate distinguishing designation opposite said situations, and a plurality of cards each of which is provided with designations corresponding to those 5 indicating the situations on the chart, said chart and each card having a like number of situations and plays respectively, and indicating on each card an unknown play to follow from the situation to which reference is made through the designations, said plays varying but representing any play which may be made from the situation as indicated on the chart, said chart being arranged and constructed to provide a series of plays which may be followed in the ordinary playing of a 15 game of baseball, and having additional designations for plays which may be used at the discretion of the players. 10

WILLIAM H. PARKER.

DAVID P. GREGORY. 20
